UNITED STATES PATENT OFFICE.

HERMAN T. SUNDSTROM, OF HOUSTON, TEXAS.

PNEUMATIC COOLING DEVICE.

1,038,022.

Specification of Letters Patent. Patented Sept. 10, 1912.

Application filed July 13, 1911. Serial No. 638,297.

To all whom it may concern:

Be it known that I, HERMAN T. SUNDSTROM, citizen of the United States, residing at Houston, in the county of Harris and 5 State of Texas, have invented certain new and useful Improvements in Pneumatic Cooling Devices, of which the following is a specification.

My invention relates to the new and useful 10 improvements in pneumatic cooling devices, and more particularly to such devices as are designed to cool the molds of linotype machines.

The object of the invention is to provide 15 a device of the character described which will eject jets of cool air against the molds carried by the mold disk of the machine, and keep said molds from becoming too hot. As is well known it is essential that 20 the metal of which the type are formed be very hot in order that the type may be perfectly formed, and the chief disadvantage of linotype machines now in common use resides in the fact that the molds thereof 25 become very hot and the matrices are heated to such a degree of temperature that they are injured by the heat.

It is the object of this invention to keep 30 the molds and matrices comparatively cool and at the same time to permit the metal from which the type are formed to attain a high degree of temperature.

Another advantage of the invention resides in the fact that in addition to keeping 35 the molds, matrices and space bands cool the jets of air also serve to keep said parts cleansed by blowing out all dust and foreign matter that may collect thereon.

With the above and other objects in view. 40 the invention has particular relation to the certain novel features of construction, operation and arrangement of parts, an example of which will be described in this specification and illustrated in the accompanying drawings, wherein:—

Figure 1, is a plan view of the mold disk showing the driving mechanism thereof and indicating, in dotted lines, my improvement attached thereto. Fig. 2, is a sectional view 50 thereof taken on the line $a-a$ of Fig. 1, and showing also the inlet tube in section. Fig. 3, is a partial detail of the improvement, and Fig. 4, is a sectional view of the detail shown in Fig. 3 taken on the line 55 $b-b$ of Fig. 3.

I referring now more particularly to the

drawings, wherein like numerals of reference designate similar parts in each of the figures, the numeral 5 refers to the mold disk which is of the usual and well known construction and which is driven by a suitable motor (not shown), through the spur gear 6. The mold disk carries two molds 7 and 8 arranged on opposite sides thereof. Each of these molds extends entirely 65 through the disk but has an overhanging flange which rests against the face of the disk through which securing screws 9 and 10 extend, which engage in tapped holes in the disk and secure the molds firmly in place. 70 Each mold is provided with an oblong slot 11 and 12, extending therethrough. These slots are arranged so as to communicate with the melting pot, (not shown), which is carried by the linotype machines, in the 75 well known manner, and the molten metal, from which the type are formed, is conducted, in the well known manner, from said melting pot to the slots of said mold and is forced therethrough against the matrices, by 80 which the type are formed, in the ordinary manner of machines of this character. The mold disk is provided with an annular groove 13 upon its face, which is concentric with said mold disk.

All of the parts hereinbefore described are now in common use on the linotype machines which are commonly used and my improvement consists of the attachments which will now be described:—Surrounding 90 the groove 13, is an annular rib, or elevation, 14 and upon this rib is secured a thin disk 15 which is secured in place by means of the screw 16 in such a manner that the disk 15 will be stationary while disk 5 rotates. The disk 15, is provided with an aperture which extends therethrough and communicates with the groove 13. A metallic tube 18 is secured to the disk 15 so as to communicate with the groove 13 through the 100 aperture 17. This tube is supported by means of a collar 19 which depends from the supporting member 20. Two tubes 21 and 22 communicate with the groove 13 and extend in opposite directions through 105 the rib 14 and point, respectively, toward the molds 7 and 8. A suitable air motor (not shown), is connected with the tube 18 by means of a suitable hose connection. The air current is forced from said motor 110 through the tube 18, and aperture 17 into groove 13 and thence through the tubes 21

and 22 against the molds 7 and 8, while the disk 5, is turning. The operative mechanism which rotates the disk 5 is so constructed that said disk can stop only in two positions, one of which is a half turn from the other. In order to cut off the air current from groove 13, when the disk 5 stops I have arranged, in said groove, two cut off valves 23 and 24, which span said groove 10 and whose outer surface is flush with the outer surface of disk 5 and contacts closely against the inner surface of disk 15. One of these valves always rests immediately beneath the aperture 17, when the disk 5 is at 15 rest and operates to cut off the current which would otherwise flow therethrough. The jets of air passing through tubes 21 and 22 are forced against the molds 7 and 8 and pass around and over the same thereby reducing the temperature thereof, and also 20 pass over the slugs thereby reducing the temperature thereof and also blowing out all dust and other foreign matter therefrom.

While I have shown and described only 25 one form of my improvement, yet I hereby reserve the right to modify the construction and arrangement of parts so long as I do not depart from the principle of the invention.

30 What I claim is:—

1. A device of the character described including the combination with a disk having an air chamber in the face thereof, of molds carried by said disk, a plate secured upon 35 said disk and covering said air chamber and having an aperture therethrough communicating with said chamber, air outlets leading from said chamber and discharging against the molds carried by said disk, and an inlet 40 tube secured to said plate and communicating with the air chamber through the aperture therein.

2. In a device of the character described the combination with a mold disk provided 45 with an air chamber and carrying molds, of a plate secured upon said disk and covering said air chamber and having an aperture

therethrough communicating with said chamber, air outlets leading from said chamber and discharging against the molds carried by the mold disk, and an inlet tube communicating with said air chamber through the aperture in said plate.

3. In a device of the character described the combination with a mold disk having 55 an air chamber therein, of molds carried thereby, the air outlets leading from said air chamber and discharging jets of air against said molds, an air inlet communicating with said air chamber and conducting 60 air thereto from a suitable generator and means closing said air inlet when said mold disk is at rest.

4. In a device of the character described the combination with a rotatable mold disk 65 having an air chamber therein, of molds carried by said disk, a plate mounted upon said disk and rotatable relative thereto and inclosing said air chamber and having an aperture therethrough communicating with 70 the air chamber, suitable discharge outlets leading from said air chamber and discharging against said molds, an inlet tube secured to said plate and communicating with said air chamber through the aperture in 75 said plate, and means closing said inlet tube when said mold disk is at rest.

5. In a device of the character described, the combination with a mold disk having 80 an air chamber therein, of a mold carried thereby, an air outlet leading from said air chamber and discharging jets of air against said mold, an air inlet communicating with said air chamber and conducting air thereto from a suitable generator and means closing 85 said air inlet when said mold disk is at rest.

In testimony whereof I have signed my name to this specification in the presence of two subscribing witnesses.

HERMAN T. SUNDSTROM.
